UNITED STATES PATENT OFFICE.

MARTIN W. HEYENGA, OF NEAR EMDEN, ILLINOIS.

SCOOP-BOARD.

SPECIFICATION forming part of Letters Patent No. 693,134, dated February 11, 1902.

Application filed June 8, 1901. Serial No. 63,860. (No model.)

To all whom it may concern:

Be it known that I, MARTIN W. HEYENGA, a citizen of the United States, residing near Emden, in the county of Logan and State of Illinois, have invented a new and useful Improvement in Scoop-Boards, of which the following is a specification.

The invention relates to improvements in end-gates.

The object of the present invention is to improve the construction of end-gates for vehicles and to provide a simple and comparatively inexpensive one of great strength and durability adapted to be readily applied to wagon-bodies and capable of being arranged to form a scoop-board and of providing an extension or platform to adapt the vehicle for the grain-elevating machine shown and described in application, Serial No. 63,861, filed by me June 8, 1901.

The invention consists in the construction and novel combination and arrangement of parts hereinafter fully described, illustrated in the accompanying drawings, and pointed out in the claims hereto appended.

In the drawings, Figure 1 is a rear elevation of an end-gate constructed in accordance with this invention, the end-gate being closed and the extension-section being arranged in a vertical position. Fig. 2 is a side elevation of the same, the extension-section being folded back. Fig. 3 is a longitudinal sectional view. Figs. 4 and 5 are detail views illustrating the manner of mounting the adjustable side brackets on the sides of the wagon-body.

Like numerals of reference designate corresponding parts in all the figures of the drawings.

1 designates an end-gate provided at its bottom with depending arms 2, arranged in eyes 3, which extend rearward from the bottom 4 of a wagon-body, whereby the end-gate is hinged to the wagon-body and is adapted to be swung downward from the vertical position (shown in Figs. 1 and 2) to the inclined or approximately horizontal position. (Shown in Fig. 3.) The arms or rods extend downward from plates 5, which are secured to the end-gate by means of bolts 6 or other suitable fastening devices, and the said bolts 6 also pass through shanks of resilient catches 7. The

resilient catches 7 are disposed horizontally, as clearly illustrated in Fig. 1 of the accompanying drawings, and their inner adjacent ends are free and are adapted to engage rods 8, whereby the end-gate is locked in a closed position. The rods, which are provided at their lower or outer ends with rings 9, have hooks 10 at their inner or upper ends for engaging eyes or openings 11 of approximately L-shaped brackets 12, adjustably mounted on the exterior of the sides 13 of the wagon-body. The L-shaped brackets have horizontal arms at their tops extending rearward from the sides of the wagon-body and provided with the said eyes or openings 11. The other arms of the brackets are arranged approximately vertically in grooves 14 of plates 15 and are provided with longitudinal slots 16 for the reception of bolts 17, passing through the slots and the plates and the sides of the wagon-body and securing the plates to the latter and retaining the brackets in their adjusted position. The vertical arms of the brackets are provided at their inner faces with corrugations 18, and the plates have corresponding corrugations or teeth arranged in the grooves 14 and adapted to be engaged by the teeth of the brackets, whereby the latter are prevented from slipping. The plates are provided at opposite sides with inwardly-extending lugs or projections 19, which are seated in suitable sockets of the wagon-body.

The end-gate is preferably provided with upper and lower cleats 20 and 21, and the upper one is extended to form laterally-projecting arms 22, which are provided with slots or openings for the reception of the horizontal arms of the brackets. When the rods are swung downward and secured in the position illustrated in Fig. 1, they extend transversely of the slots or openings of the arms 22, and the end-gate is thereby securely locked in its open position.

The end-gate is supported when swung downward to form a scoop-board by means of the rods 8 and the rings engaging the laterally-projecting arms 22 and forming stops for the same. In order to prevent the end-gate from slipping when it is arranged to form a scoop-board, a hook 23 is provided. This hook, which depends from the lower portion of the end-gate, has a lower engaging portion

and is provided with an upper slotted shank 24, receiving a suitable fastening device for adjustably securing the hook to the bottom cleat 21 of the end-gate. The depending catch or hook 23 engages a beveled block 25, secured to the lower face of the bottom of the wagon and arranged as illustrated in Fig. 3 of the drawings.

The end-gate is provided at opposite sides with suitable wings 26, and it has an extension-section 27 hinged to its upper edge and adapted to be arranged in the same plane as the end-gate when the latter is lowered to form a platform or scoop-board. The hinges 10 are composed of upper and lower leaves or sections 28 and 29, secured to the end-gate and to the extension-sections by bolts or other suitable fastening devices. The lower leaves or sections are preferably provided with horizontal pintles, and the upper leaves or sections are provided with eyes for the reception of the pintles and are adapted to be detached by removing the bolts to permit the extension-section to be removed. The extension-section 15 is supported by folding braces arranged at opposite sides of the end-gate and composed of sections or bars 30 and 31, hinged at their adjacent ends by a suitable pindle 32 and pivoted or hinged at their other ends to arms 33 and 34 of the extension-section and the end-gate. The sections of the folding braces are provided at their adjacent ends with shoulders adapted to abut when the sections are arranged in alinement, as illustrated 20 in Fig. 3 of the drawings, whereby the braces will support the extension-section in position for use. The sections or bars are adapted to swing outward to permit the extension-section 25 to swing downward. The extension-section 27 and the end-gate are provided with rack-bars 30 and 36, adapted to form a continuous rack to receive feed mechanism of the grain-elevating machine of the said application. The extension-section is adapted to receive and 35 support the machine, and it forms a space for 40 45

the operator while the said machine is being started.

What I claim is—

1. In a device of the class described, the combination with a wagon-body, of an end-gate, an extension-section hinged to the end-gate and adapted to form a continuation thereof to provide a platform, a rack supported by the end-gate and the extension-section, and means for supporting the end-gate and the extension-section in position for forming a platform, substantially as described. 50

2. In a device of the class described, the combination with a wagon-body, of an end-gate, an extension-section hinged to the end-gate at the top thereof and adapted to form a continuation of the same, means for supporting the end-gate, and a folding brace connected with the end-gate and with the extension-section and adapted to support the latter and capable of permitting the same to swing downward, substantially as described. 60

3. In a device of the class described, the combination with a wagon-body, of an end-gate, an extension-section hinged to the end-gate at the top thereof, arms extending from the end-gate, and the folding braces composed of sections hinged together at their adjacent ends and pivoted at their outer ends to the arms of the end-gate and to the extension-section, substantially as described. 70

4. In a device of the class described, the combination of a wagon-body having eyes at its bottom, an end-gate provided with arms detachably engaging the eyes, the beveled block secured to the bottom of the body, and the depending hook or catch arranged to engage the block when the end-gate is swung downward, whereby the arms are retained in the eyes, substantially as described. 80
